UNITED STATES PATENT OFFICE.

BOHUMIL KLECAK, OF NEW YORK, N. Y., ASSIGNOR TO VAN KANNEL REVOLVING DOOR COMPANY, OF NEW YORK, N. Y., A CORPORATION OF NEW JERSEY.

REVOLVING DOOR.

1,055,474.

Specification of Letters Patent. Patented Mar. 11, 1913.

Application filed July 25, 1911. Serial No. 640,455.

To all whom it may concern:

Be it known that I, BOHUMIL KLECAK, a citizen of the United States, residing at New York, borough of the Bronx, in the 5 county of New York and State of New York, have invented certain new and useful Improvements in Revolving Doors, of which the following is a specification.

This invention relates to improvements in 10 revolving doors, and more particularly to mechanism for locking the wings together whereby they are maintained in proper relative position with relation to the central pivot or spindle.

15 The object of the invention is to provide a mechanism that will permit the wings to collapse when abnormal pressure is applied to any of the wings, so that in case of emergencies, where it is desired to have a free 20 passageway, the wings may be automatically collapsed.

A further object of the invention is to provide a construction wherein the wings, when the ordinary operating pressure is applied to them, will have a slight yielding or cushioning movement, so that in practice, 25 the particular wing against which pressure is applied, will move slightly before the whole structure or the revolving parts thereof, will begin to revolve, the movement, however, being short of that required to disengage the locking devices, as would be desired in an emergency.

The general construction in the particulars of mounting the wings upon the spindle is as shown and described in a patent granted to Theophilus Van Kannel, Number 836,843, dated November 27, 1906, and the invention about to be described, as above 30 suggested, resides more particularly in the locking devices for the wings, and in view of this fact, the mechanism for mounting the doors upon the spindle will not be herein described and illustrated, further than is 35 necessary to illustrate and explain the manner of the folding of the doors, with relation to the locking devices.

In the drawings—Figure 1 is an elevation of a revolving door structure, the parts being in normal position; Fig. 2 is a plan

view; Fig. 3 is a plan view of the upper supporting disk, with the doors collapsed and folded to one side thereof, only a portion of the wings being shown; Fig. 4 is a broken horizontal section of two of the 55 wings, taken through the locking devices, the wings being shown in the relation they will occupy when extended and locked; Fig. 5 is a vertical section of the locking device; Fig. 6 is a face view or elevation of 60 one side of the locking device.

Referring to the drawings, the numeral 1 designates the door wings, which, when in normal position occupy positions at right angles with relation to a central spindle 2 65 suitably supported at the top and bottom of the casement, and with which the wings revolve. Rigidly secured to the spindle 2, near the upper end thereof, is a supporting disk 3, having a channel 4 therein. Keyed 70 to the spindle, adjacent to the disk is a pinion 5, whose teeth mesh with toothed segments 6 carried by the several wings 7 of the door. Each wing is provided with a spring-pressed stud 8 which runs in the 75 channel 4, whereby the wings are guided with relation to the central pivot, when the door is collapsed in an emergency, or when the wings are folded, as shown in Fig. 3, for the purpose of removing the door from 80 the casement, or folding all of the wings in the same direction, so as to permit a passageway in either direction, through the casement. The channel is divided quarterly 85 with sockets or depression 8', for the reception of the ends of the studs, the positions in which the studs enter the sockets, representing the proper positions of the wings when they are extended into operative position.

At the lower end of the wings, the mechanism just described, is duplicated, the difference, however, being that the parts are inverted, so that the channel 4 would open toward the foundation or bottom of the 95 casement, rather than toward the top, as in the case of the upper structure.

The mechanism for mounting the doors need not, it is thought, be further described, since from the foregoing description, it will 100

be seen that all of the wings are individually movable with regard to the spindle, and the locking mechanism in which this invention resides, will now be described.

5 The numerals 9 and 10 designate the two main plates which are clamped together on the wings of the door, by means of screws 11 which screws extend through one of the plates into suitable bosses in the opposite plate.

10 The numeral 12 designates a sliding plate whose outer face works against the inner face of the plate 10. The plate 12 is provided at one side with an upwardly projecting flange 13, which carries a lateral projection 14, surrounded by one end of a spiral spring 15, whose other end surrounds a stud 16 carried by the plate 9. The plate 9 is recessed as shown at 17, for the reception 15 of a knuckle-casting 18 pivotally mounted upon a stationary pin 19. Held in the casting 18, and partially surrounding the pin 20, is a yoke-shaped spring 21, which receives the flattened end 22 of a flexible cable 23. Surrounding the pin 19 with one end 20 set into the pin, and the other in a cross piece 24, is a spiral spring 25 exerting a tendency to keep the whole knuckle casting, and parts carried thereby, rocked toward 25 the bottom of the recess 17 in the plate 9, for a purpose that will presently appear. The plate 12 is provided with an aperture 26 adapted to receive the head 27 on one end of the cable 23. This aperture connects 30 with a smaller aperture 28 in the plate 12, by a channel 29. The aperture 26 is of sufficient size to easily receive the head 27 of the cable, which, when inserted, the cable may be slid along through the channel until 35 the head comes opposite the smaller aperture 28, which aperture being smaller than the head, prevents this end of the cable from pulling out, it being obvious that this side of the plate forms what may be regarded as 40 the permanent fastening for the cable. To prevent the head 27 of the cable from slipping back toward the large recess, I preferably provide a short screw 30.

50 Located between the plates 9 and 10 is an internally threaded casting 31 through which passes a threaded stem 32 carrying on its forward end, a wheel 33 having sockets 34 therein for the reception of the end of a pointed instrument, by which the wheel 55 and stem may be turned. The end of the stem abuts against a flange 35 on the plate 10, which flange in turn abuts against the inner wall of the recess 17 of the plate 9, so that by turning the wheel, the threaded stem 60 may be worked through the casting 31, thus, when the screws are loosened in the plates 9 and 10, the whole lock may be slid either in or out, as the occasion may require, for the adjustment of the cables.

In operation, the wings are put in proper 65 position at right angles to the spindle, and the heads 22 of the cables are inserted into the yoke-shaped springs 21, one of which is carried by each wing. The door may now be revolved with all of the wings properly 70 locked together by the cables. In operating the door, when pressure is brought against one of the wings, under ordinary conditions, and when, of course, it will not be desired to break the lock between the wings, such 75 pressure, enough to start the door revolving will cause the particular wing upon which pressure is being applied, to yield slightly, this yielding motion being permitted by the pull upon the cable 23, which will cause the 80 plate 12 to slide slightly upon the plate 10 and against the influence of spring 15. As soon as motion is imparted to the door, the particular wing will immediately resume normal position, and all of the cables will 85 tighten up and remain taut, throughout the movement that follows the initial movement of starting the door. Under ordinary operating pressure, of course the lock is not intended to be broken, but in an emergency, 90 or when it is desired to fold the doors, the heads 22 of the cable are pulled out of the yoke-shaped springs. The tension of these 95 springs is such that they will hold the cables under ordinary pressures, but will permit the heads 22 to be pulled out if excessive pressure is exerted, for the purpose described.

Having thus described my invention, what I claim as new is:

100

1. In a revolving, collapsible door, the combination with the wings thereof, of cables connecting the wings together, one end of each cable being held in fixed position to one face of each wing and the other end of each cable detachably-held to the adjacent face of the opposite wing by a spring-actuated knuckle, whereby the tension force of the spring is being constantly exerted to depress the cable-holding end of the knuckle, 105 so as to maintain the cables in taut condition.

2. In a revolving collapsible door, the combination with the wings thereof, of cables connecting the wings together, one end of each cable being held in fixed position to one face of each wing and the other end of each cable detachably-held to the adjacent face of the opposite wing by oppositely-disposed spring-arms carried by a pivoted knuckle, and a tension-means carried by 115 each knuckle, the tension force of the spring being constantly exerted to hold the spring-arms in a downward direction, so as to maintain the cables in taut condition.

3. In a revolving, collapsible door, the 125 combination with the wings thereof, of plates attached to adjacent faces of said wings, cables connecting the wings together,

one of said plates being provided with means for holding one end of the cables in fixed position and the other with a pivoted knuckle having spring-arms for detachably holding the other end of the cables, and a spring carried by said knuckle, the tension force of which is constantly exerted to hold the spring-arms in a downward direction,

whereby the cables are automatically maintained in taut condition. 10

In testimony whereof I affix my signature in presence of two witnesses.

BOHUMIL KLECAK.
